M. FUCCI

COMBINED TAIL LIGHT AND NUMBER PLATE BOX

Filed Aug. 29, 1923

INVENTOR.

Massimo Fucci

G. H. Braddock
ATTORNEY.

UNITED STATES PATENT OFFICE.

MASSIMINO FUCCI, OF BRIDGEPORT, CONNECTICUT.

COMBINED TAIL LIGHT AND NUMBER-PLATE BOX.

Application filed August 29, 1923. Serial No. 659,967.

To all whom it may concern:

Be it known that I, MASSIMINO FUCCI, a subject of the King of Italy, and resident of Bridgeport, in the county of Fairfield and 5 State of Connecticut, have invented certain new and useful Improvements in Combined Tail Lights and Number-Plate Boxes, of which the following is a specification.

This invention relates to a casing or box 10 of the type adapted to house a lamp at the rear of a wall of said casing or box constructed to serve, when said lamp is lighted, as a combined tail light and illuminated number plate.

15 An object of the invention is to provide a novel, simple and inexpensive box of the present character, the lid or cover of which, assisted by light from a lamp in the box, can serve as a tail light and illuminated number plate, and the remainder of which 20 will consist of two pieces of metal and a few rivets, one of said metal pieces being a blank shaped to constitute the body of the box, and the other of said pieces being a reinforcing band extending about and associated 25 with said body in unique manner.

A further object is to equip the casing or 30 box with a slotted metal strap, integral with the metal of said body, for easily and conveniently securing the improved device in 35 proper position at the rear of an automotive vehicle.

With the above and other objects in view, the invention comprises the construction, arrangement and combination of parts as now 40 to be fully described and as hereinafter to be specifically claimed, it being understood that the disclosure herein is merely illustrative, slight changes in details of construction and arrangement of parts being permissible so long as within the spirit of the invention 45 and the scope of the appended claims.

In the accompanying drawing forming a part of this specification,

45 Fig. 1 is a perspective view of the novel device, the lid or cover being shown in open position;

Fig. 2 is a sectional view, on an enlarged scale, taken on line 2-2 in Fig. 1, the 50 casing lid or cover and its hinges being not shown;

Fig. 3 is a sectional view, on an enlarged scale, taken on line 3-3 in Fig. 1; and

55 Fig. 4 is a plan view, on a reduced scale, of a blank of metal for constructing the body of the casing or box.

With respect to the drawing and the numerals of reference indicated thereon, 10 is a blank of metal for constructing the body of the casing, 11 denoting the portion of the 60 metal adapted to constitute the base or bottom, 12 and 13 the portions adapted to constitute the side walls, and 14 and 15 the portions adapted to constitute the end walls of 65 said body. To provide said base and said side and end walls, the metal of the blank may be bent upwardly at right-angles along the dotted lines *a*, Fig. 4, together comprising a rectangle, so that adjacent edges of 70 said side and end walls closely meet, and flaps 16 at the extremities of said end walls may afterwards be given a right-angle bend along the dotted lines *b*, Fig. 4, to be contiguous with the side walls 12 and 13, respectively. As shown, the flaps 16 engage 75 the inner faces of the side walls (see Fig. 1), but clearly, they could just as well be contiguous with the outer faces of said side walls. Or certain of the flaps could be associated with the side walls to engage the 80 end walls, should this be considered preferable.

Numeral 17 denotes a strip of metal, preferably of some considerable thickness and of width equal to approximately one-half the 85 depth of the casing body, adapted to completely surround the upper portion of said body to be contiguous with the side walls 12 and 13 and the end walls 14 and 15 to serve 90 as a reinforcing band insuring the fixed relation of the side and end walls to each other. The ends of the strip 17 can terminate, desirably closely adjacent each other, at one corner of the casing, in which event the strip would have three right-angle bends, or said 95 strip can have four right angle bends, with ends terminating at some location not a corner, as will be understood.

The application of the reinforcing band to the side and end walls of the casing body is 100 the next step in its construction. The band can be shaped directly to said walls, or it can be formed and afterwards slipped onto the partially constructed body. In either event, it is placed and held so that its edge 105 opposite the base 11 of the casing body is arranged approximately at the location indicated by the dotted lines *c*, Fig. 4, denoting the limits of said side and end walls, and consequently, indicating the upper edge of 110 the finished casing body, while metal strips, denoted 18, of said blank, immediately be-

yond said dotted lines *c*, are bent along said lines *c* over one edge as at 19, down against the outer face, as at 20, and under the opposite edge, as at 21, of said reinforcing band, 5 as shown more clearly in Figs. 2 and 3, to provide housings, denoted 22, locking the band to each side and end wall of the casing body.

Three of the metal strips 18 are shown as 10 terminating adjacent the location 21, while the fourth, the upper one in Figs. 1 and 3, merges at said location into a strap holder 23 lying against and secured to the side wall 12 as by means of rivets 24. Numeral 25 15 denotes a metal strap with slots 26 for securing the device in proper position at the rear of an automotive vehicle. As disclosed, the strap is approximately in alignment with the base 11 of the casing body, it being a 20 continuation of the strap holder 23, the dotted line *d* on the blank of Fig. 4 denoting the location of the right-angle bend 27 between said holder and strap. Evidently, the integral strap could be associated with 25 the casing body in some other suitable manner.

Numeral 28 represents a wire having a lamp socket 29 situated in the base 11 of the casing body, and 30 represents a light bulb 30 screwed into the socket and located in the box. 31 is a lid or cover for the box which may be hinged thereto as at 32, 33 indicating, generally, a detachable fastener for the lid or cover. This lid or cover is adapted to 35 serve, with the aid of light from the lamp 30, as a combined tail light and illuminated number plate, and may be of any suitable construction to this end. Usually, there is a colored disc, denoted 34, ordinarily red, 40 directly above the lamp, and number and

character perforations, denoted 35, customarily above a glass closing plate (not shown) carried by the lid or cover.

Attention is invited to the fact that the casing can be used indefinitely, the only 45 change necessary from year to year, or when a different number plate is required, being the removal of the old lid or cover and the substitution of a new one. Obviously, the 50 number and character perforations 35 of the number plate will be discernible by day.

Having thus fully described the invention, what I claim as new and desire to secure by Letters Patent is:

1. A device of the character described, 55 comprising a casing having a lamp therein and consisting of a single piece of metal shaped to constitute the body of said casing, a metal hanging strap integral with said body, a reinforcing band about said body, 60 and a removable cover independent of said reinforcing band upon said body adapted to constitute, aided by light from said lamp, a tail light and illuminated number plate.

2. A tail light and number plate box, 65 comprising a body having a lamp therein and consisting of a single piece of metal including a base, side and end walls, and locking strips, a reinforcing strip about the upper edges of said walls and beneath said locking 70 strips, the locking strips serving to lock the reinforcing strips to the walls, and a removable cover independent of said reinforcing strip upon said body and adapted to constitute, aided by light from said lamp, a tail 75 light and illuminated number plate.

Signed at Bridgeport, in the county of Fairfield and State of Connecticut, this 24th day of August, A. D. 1923.

MASSIMINO FUCCI.
